DESIGN FOR A GROOMING TRAY

Burton J. Barnett, Los Angeles, Calif.

Application January 24, 1947, Serial No. 136,363

Term of patent 3½ years

(Cl. D86—10)

To all whom it may concern:

Be it known that I, Burton J. Barnett, a citizen of the United States, residing at Los Angeles, county of Los Angeles, and State of California, have invented a new, original, and ornamental Design for a Grooming Tray, of which the following is a specification, reference being had to the accompanying drawing, forming part thereof.

Fig. 1 is a three-quarter perspective view of the grooming tray showing my new design.

Fig. 2 is an end elevational view thereof.
The back of the tray is unornamented.

I claim:

The ornamental design for a grooming tray, substantially as shown and described.

BURTON J. BARNETT.
